HEARING AID

Robert L. Geib, Wayzata, Minn., assignor to Dahlberg Electronics, Inc., Minneapolis, Minn., a corporation of Minnesota

Filed Feb. 1, 1966, Ser. No. 834

Term of patent 14 years

(Cl. D26—14)

FIG. 1

FIG. 2

FIG. 3

FIG. 4

FIG. 1 is a side elevational view of a hearing aid showing my new design, the opposite side being substantially a mirror image;

FIG. 2 is an end elevational view thereof as seen from left to right of FIG. 1;

FIG. 3 is a top plan view thereof, the bottom being substantially a mirror image; and

FIG. 4 is an end elevational view thereof as seen from right to left of FIG. 1.

The dominant features of my invention reside in the portions shown in full lines.

I claim:

The ornamental design for a hearing aid, as shown and described.
